Attorneys

UNITED STATES PATENT OFFICE.

GEORGE E. JORDAN, OF PERRY, GEORGIA.

SAFETY ARRANGEMENT FOR RAILROAD CROSSINGS.

Application filed May 1, 1928. Serial No. 274,287.

This invention relates to safety arrangements for railroad crossings, and more particularly to devices of this character which are placed in the roadway near the crossing so as to check the speed of oncoming vehicles and force the drivers thereof to give their attention to the railroad crossing.

It has been proposed to provide a ramp or hump structure across the path of traffic adjacent the railroad crossing so that the jolting of the vehicle passing over such obstruction will forcibly call the attention of the driver to the proximity of the railroad crossing. The ramp portions also serve the purpose of checking the speed of the vehicle so that proper precautions can be taken.

However, such arrangements are for the purpose of controlling automobile or high speed traffic, and impose an unwarranted hardship upon horse-drawn vehicles, the speed of which is such that the ramp structure is unnecessary.

It is therefore an object of the present invention to provide a device of this character with means whereby horse-drawn vehicles may pass without interference from the ramp structure.

In order to prevent reckless drivers from driving around the safety ramps heretofore proposed, they have been so arranged that all traffic must pass over the ramp before crossing the railroad. However, many emergency conditions arise in which it is a great disadvantage not to be able to drive around the ramp, as in the case of the passage of government motor transport equipment or troops.

It is therefore another object of the invention to provide a safety ramp structure with arrangements whereby authorized traffic may pass around the ramp.

Another object of the invention is to provide an arrangement whereby automobile traffic is forced to pass over the ramp in approaching a crossing, but is permitted to pass by the ramp in leaving the crossing.

Still another object of the invention is to provide an automatic one-way traffic control device which will serve as a bar to traffic in one direction, but will allow passage of traffic in the other direction.

Other objects and features of novelty will be apparent from the following description and the accompanying drawings, in which:

Figure 1 is a plan view of a highway rail-

road crossing showing the safety arrangements according to the present invention;

Figure 2 is a vertical cross section taken along the line 2—2 of Fig. 1;

Figure 3 is an elevation of the railroad crossing as it appears to oncoming traffic; and

Figure 4 is a detail view of the one-way traffic device.

Referring more particularly to the drawings, a railroad crossing has been illustrated, in which a highway 5 passes over railroad tracks including rails 6, 7, 8 and 9. This crossing has been provided with safety arrangements according to the present invention, and a ramp structure indicated generally at 10 is placed in the highway in the path of the right hand or approaching traffic, so as to substantially occupy one-half of the width of the highway. This ramp may be of any desired construction or material, so long as it is of sufficient strength to withstand the traffic loads. Concrete is very satisfactory for this purpose.

The ramp 10 is somewhat longer than the average vehicle and has a smoothly curved upper surface comprising a main incline 11, a hump 12, a trough 13 and a depression 14 formed by two smaller humps 15 and 16. Beyond the hump 15 the ramp terminates in a short incline 17.

An automobile passing over this structure will first ride up the incline 11 over the hump 12 into the trough 13. If the car approaches at high speed, this arrangement will cause considerable jolt to the vehicle, which will check its speed and force the driver to give his attention to the railroad crossing, and apply his brakes. However, if the car approaches at proper speed, it can pass over with no discomfort. The front wheels riding over the first small hump 16 will tend to further check the vehicle so that it will come to rest with its front wheels in the smaller trough 14. The trough 14 is spaced from the nearest rail of the railroad crossing a sufficient distance to allow adequate clearance for the rolling stock, so that an automobile with its front wheels resting in the trough 14 will be entirely safe.

When the crossing is clear the driver may release his brakes and drive the front wheels of the car over the hump 15. The front wheels will then ride down the incline 17 and the rear wheels at the same time ride down

into the trough 13, imparting sufficient momentum to the car to assist in carrying it over the humps 15 and 16 and thus permit a rapid get-a-way.

5 As shown in Fig. 3, hump 10 is constructed of two spaced portions 20 and 21 having between them a clear channel 22, the bottom of which is the normal roadway surface. This channel permits the passage of horse-drawn 15 vehicles which have much greater road clearance than automobiles.

The highest hump 12 of the ramp 10 is of greater height than the clearance of the average automobile, so that if the driver attempts 20 to pass by allowing the automobile wheels to pass through the channel 22, the crank case or other parts of the automobile will engage with the hump 12, which will prevent its passage. However, with horse-drawn vehicles 25 the horse may walk in the channel 22, with the wheels of one side passing through the channel 22 and the wheels of the other side passing outside of the ramp 10. In the case of a two-horse vehicle the second horse 30 may walk outside of the ramp. A curb 25 is provided for each outer edge of the ramp 10 in order to prevent automobiles from slipping or skidding off the ramp.

In order to prevent reckless drivers from 35 merely driving around the ramp, the left hand side of the highway is provided with a swinging obstruction 26 comprising a flat member such as a board, of sufficient height to offer an obstruction to the passage of traffic, and extending substantially across the entire left hand side of the roadway. The side of the member 26 toward the oncoming traffic is painted with a warning sign as large and conspicuous as possible, as shown in Fig. 40 3, and a pedestal 27 is preferably placed in the center of the roadway and provided with a warning sign 28 at the top.

The member 26 is hinged at its intersection 45 with the highway as by means of eyes 30 portably resting in sockets formed in the surface of the roadway. Counterweights 31 and 32 are provided for the member 26 and serve to hold it erect under normal conditions, and also form braces to strengthen it 50 against accidental impact.

It will thus be readily apparent as shown 55 in Fig. 3 that the member 26 appears to oncoming traffic as a barricade and the ramp structure appears open so that the traffic will be directed to the ramp. However, as shown in Fig. 1, after the ramp is passed and the railroad tracks are crossed, the vehicle leaving the tracks must pass over the member 26. The driver merely approaches the member 60 26 at comparatively slow speed and the front wheels of the vehicle engaging the top of the member 26 swing it down about its pivot, as shown in Fig. 4, against the action of the counterweights 31 and 32.

65 From the foregoing description it will be

readily apparent that the safety arrangements according to the present invention are automatic and fool-proof, and will take care of travel for long periods of time without any attention. However, in the case of emergency 70 conditions, when it is necessary to have traffic pass over the highway as quickly as possible and the passage of trains has been taken care of, the members 26 may be removed by pulling the eyes 30 out of their sockets and 75 the emergency traffic may pass around both ramps at comparatively high speed.

While the preferred embodiment of the invention has been shown and described in great detail, it will be obvious that the broad 80 idea is susceptible of many modifications and alterations, and therefore the scope of the invention is not limited to the exact details shown and described, but includes such embodiments of the broad idea as come within 85 the scope of the appended claims.

Having thus described the invention, what is claimed as new and desired to be secured by Letters Patent is:

1. A safety traffic speed control apparatus 90 for highways, comprising in combination, a permanent speed obstruction stationed in one-half of the highway, and a portable automatic one-way traffic device stationed in the other half of the highway. 95

2. A safety traffic speed control apparatus for highways, comprising in combination, a permanent speed obstruction stationed in one-half of the highway, and a barricade pivoted across the other half of the highway, 100 said barricade having counterweight structure permitting the barricade to swing down to permit traffic to pass in one direction, but causing the barricade to swing up to prevent traffic in the opposite direction. 105

3. In a highway, a pair of obstructions occupying substantially the entire width of the highway, one of said obstructions being permanent, and provided with an undulating surface over which traffic may readily pass at 110 proper speed, and the other being portable, permitting an emergency by-pass of the traffic.

4. A safety traffic speed control apparatus for highways, comprising a hump stationed 115 in the path of the traffic, said hump having channels therethrough permitting the passage of the wheels of horse-drawn traffic, but of such depth as to exclude motor vehicle traffic therefrom thereby causing its wheels to 120 pass over the hump.

5. In a highway having a zone in which conditions require slow speed traffic, a permanent obstruction in the path of the entering traffic, and a one-way obstruction permitting 125 the exit of traffic leaving said zone.

6. In a highway having a zone in which conditions require slow speed traffic, a permanent obstruction in the path of the entering traffic, and a one-way obstruction permitting 130

the exit of traffic leaving said zone, said one-way obstruction being portable to permit emergency high speed entrance and exit.

7. A safety traffic control device for highways comprising an elongated obstruction arranged transversely of the path of the traffic forming an effectual bar to traffic in one direction, said member being pivotally mounted to swing about an axis transverse to the path of travel to an inoperative position under the weight of the traffic to permit such traffic to pass thereover in the opposite direction.

8. A safety traffic control device for highways comprising an elongated obstruction arranged transversely of the path of the traffic forming an effectual bar to traffic in one direction, said member being pivotally mounted to swing about an axis transverse to the path of travel to an inoperative position under the weight of the traffic to permit such traffic to pass thereover in the opposite direction, and means for returning said obstruction to operative position when the traffic has passed.

9. A traffic control device comprising a permanent obstruction having a smooth surface curved in the direction of travel, said curved surface rising above the normal highway surface a distance greater than the road clearance of automobiles, and straight channels in said surface, dividing said obstruction into a plurality of portions of width greater than the wheel tread of automobiles, whereby automobiles pass over the curved surface, but other traffic having different wheel tread may straddle the curved surface.

10. A highway having two transversely aligned obstructions extending substantially the entire width thereof, one of said obstructions comprising a hump over which vehicles may pass by rising above the normal surface of the highway, and the other comprising a one-way device adapted to yield to permit vehicles to pass in one direction, but to form a rigid bar to traffic in the opposite direction.

In testimony whereof I hereunto affix my signature.

GEORGE E. JORDAN.
